LIQUID FUEL COMBUSTION APPARATUS

Henry J. De N. McCollum, Chicago, Ill.; Thelma
McCollum executrix of said Henry J. De N.
McCollum, deceased

Application September 8, 1941, Serial No. 410,039

4 Claims. (Cl. 158—28)

My invention relates generally to liquid fuel combustion apparatus, and more particularly to improved means for maintaining combustion of a combustible mixture of liquid fuel and air in a confined combustion chamber.

It is an object of my invention to provide an improved means for causing rapid and complete combustion of a liquid fuel and air mixture in an enclosed combustion chamber.

A further object is to provide an improved re-igniter for igniting a fuel mixture in the event that the flame becomes accidentally extinguished.

A further object is to provide an improved means for introducing a combustible mixture into a confined combustion chamber to secure rapid and complete combustion.

Other objects will appear from the following description, reference being had to the accompanying drawing, in which:

Fig. 1 is a central vertical sectional view of a combustion chamber for the burning of a liquid fuel and air mixture;

Figs. 2 and 3 are transverse sectional views taken on the lines 2—2 and 3—3, respectively, of Fig. 1.

As shown in Fig. 1, a combustion chamber 10 is formed in a combustion chamber casting 12 provided with a hollow cylindrical liner 14. The liner 14 may be of stainless steel or other suitable heat and corrosion resistant metal. The fuel mixture is supplied through an induction tube 16 which is removably secured to the casting 12 by a nut 18, the inner end of which projects a substantial distance into the combustion chamber 10.

The induction tube is provided with a plurality of radial ports 20, which may be formed as indicated in Fig. 2, by punching vanes 22 inwardly. The ports 20 are substantially flush with the bottom of the combustion chamber 10, and the fuel mixture is deflected towards the ports 20 by the generally conical surface 24 of a plug 26 suitably secured at the upper end of the induction tube. As a result of the provision of the vanes 22, a rotary motion is imparted to the fuel mixture entering the combustion chamber 10 so that it travels upwardly through this chamber in generally helical paths. This facilitates complete combustion of the mixture, especially at high fuel feed rates.

The fuel mixture is adapted to be ignited by an electrical resistance wire igniter 26 suitably secured in an igniter housing 28, the igniter and housing being preferably of the construction

more fully disclosed and claimed in my prior Patent No. 2,191,178.

The products of combustion flow outwardly from the combustion chamber through passageways 30 formed in a heat exchanger assembly 32, the heat exchanger being provided with longitudinal fins 34 and a muffling filler 36, all as more fully disclosed in my copending application Serial No. 378,262, filed February 10, 1941, now Patent No. 2,379,017 issued June 26, 1945.

Due to possible irregularities in the rate of supply of the fuel mixture and to other possible irregularities in the operation, the flame in the combustion chamber 10 may occasionally become extinguished. Since it takes some time for the resistance wire 26 to become heated to incandescence, and since this igniter is controlled by suitable thermostatic or other switches, so as to be deenergized as soon as combustion takes place initially, it is desirable to provide some means for reigniting the flame should it become accidentally extinguished. The means which I have provided for this purpose comprises a spirally coiled sheet 40 preferably made of a nickel chromium alloy, such as "Nichrome-V" or "Inconel," which are highly resistant to deterioration by the high temperatures involved and by the gases of combustion which are present in the combustion chamber. The spirally coiled sheet 40 is preferably in central position in the combustion chamber 10, as by welding its outer coil to the extremity of the induction tube 16.

The adjacent coils of the re-igniter are spaced from one another slightly to provide a spirally shaped pocket 42 in which the combustible mixture may collect and in which its flow is greatly impeded. As indicated in Fig. 3, the outer end of this spiral sheet-like pocket 42 faces in a direction opposite to that in which the fuel mixture flows (as indicated by the arrows) so that upon accidental extinguishment of the flame in the combustion chamber, the combustible mixture will tend to enter the pocket 42, but since the only factor tending to cause the mixture to flow into the pocket will be that of the inertia of the fuel mixture, the flow into the pocket will be relatively slow, so that the adjacent walls of the re-igniter sheet 40 will not be rapidly cooled by the mixture. Instead, the re-igniter sheet will rapidly heat the combustible mixture to a sufficiently high temperature to cause it to ignite, and the expansion due to combustion within the pocket will result in ejection of a flame from the pocket, thus causing re-ignition of the mixture within the combustion chamber 10.

To cause such re-ignition, the re-igniter must have sufficient mass to retain its high temperature for a considerable length of time, and should be so mounted that heat will not escape therefrom very rapidly by conduction. The form of the igniter should also be such that it is not rapidly cooled by radiation, or by the flow of the combustible mixture past it. A further requirement is that the re-igniter shall have means which will permit the combustible mixture to flow rather slowly to that portion of the re-igniter which is at the highest temperature.

The spirally coiled sheet 40 admirably fulfills these conditions, since but a small portion of the heat contained therein upon accidental interruption of combustion is conducted from its outer coil to the induction tube 16. Only the outer surface of the outer coil of the re-igniter is partially cooled by radiation and by the flow of the combustible mixture past it. The inner coils of the re-igniter are thus enabled to retain their heat for a long period of time, and the combustible mixture can reach the inner coils through the spiral sheet-shaped pocket 42.

Since the re-igniter is made of a corrosion-resistant metal alloy, there is no danger of fragments of the re-igniter being carried from the heater with the exhaust gases. It will be understood that in many installations on airplanes the fuel mixture is supplied from the airplane engine supercharger at a point at which the pressure is relatively high, and the products of combustion from the heater are returned to the supercharger at a point at which the pressure is relatively low. Thus, if the re-igniter were of a type which might break or disintegrate, much damage might be done in the airplane engine by fragments of the re-igniter. It is for this reason that the re-ignition means herein disclosed is preferred over the re-ignition means shown in my aforesaid prior application whenever the heater exhaust is returned to the engine supercharger.

It will be understood that the heater assembly is entirely enclosed so that neither the combustible mixture nor the products of combustion can be diluted by or escape to the atmosphere. Furthermore, the difference in pressure between the induction tube 16 through which the combustible mixture is supplied and the exhaust of the heater is relatively great, so that the flow of the mixture through the combustion chamber is at high speed. By having the flow through the heater at very high speed, and supplying efficient heat exchange apparatus, the size and weight of the heater may be reduced to a minimum, making the heater very practical for use on aircraft. However, the fact that flow through the heater is at such high speed greatly increases the problem of re-ignition. I have found, however, that the re-igniter disclosed herein functions satisfactorily under the most adverse conditions of operation.

While I have shown and described a particular embodiment of my invention, it will be understood by those skilled in the art that the objects of the invention may be attained by the use of constructions differing in shape and form from that disclosed without departing from the underlying principles of the invention. I therefore desire, by the following claims, to include within the scope of my invention all such variations and modifications by which substantially the results of my invention may be obtained through the use of substantially the same or equivalent means.

I claim:

1. In a heater for burning a fuel and air mixture, and having a combustion chamber, a re-igniter for causing re-ignition of the flame in the combustion chamber should it become accidentally extinguished, comprising a spirally coiled sheet of a heat and corrosion resistant metal alloy, with adjacent coils of the sheet separated to provide a spiral sheet-like pocket of greater width than thickness.
- 15 2. In a heater, the combination of means providing a combustion chamber, an induction tube for said heater projecting into said combustion chamber and having radial openings therein, means on said induction tube adjacent said openings for causing fuel mixture flowing from said induction tube into said combustion chamber to follow a generally helical path through the combustion chamber, and a heat and corrosion resistant metal alloy re-igniter secured to the end of said induction tube and providing a pocket for the reception of the fuel mixture, said pocket having an opening facing in a direction opposed to the direction of helical flow of the fuel mixture.
- 25 3. A re-igniter for use in the combustion chamber of a heater for re-igniting the combustible mixture therein should the flame become accidentally extinguished comprising, a spirally coiled rigid sheet of a heat and corrosion resistant metal alloy including a plurality of turns spaced from one another to provide a spiral sheet-like passageway between the turns, the outer end of said passageway adapted to face in a direction opposite the general direction of flow of the combustible mixture through the combustion chamber.
- 30 4. A re-igniter for use in a combustion chamber burning a combustible mixture of fuel and air comprising, a rigid sheet metal structure supported at one end and providing a plurality of portions one within the other with the space between said portions forming a passageway of
- 35 45 50 55 60 55 thickness less than one-tenth of its width and opening into the combustion chamber at one end and at one side of said structure.

HENRY J. DE N. MCCOLLUM.
